UNITED STATES PATENT OFFICE.

NATHAN GOLDSMITH, OF NEWARK, NEW JERSEY.

DESIGN FOR A CORNER PIECE FOR TRUNKS, SUITCASES, AND THE LIKE.

Application filed March 18, 1922. Serial No. 1,230. Term of patent 3½ years.

To all whom it may concern:

Be it known that I, NATHAN GOLDSMITH, a citizen of the United States, residing at Newark, in the county of Essex and State of New Jersey, have invented a new, original, and ornamental Design for Corner Pieces for Trunks, Suitcases, and the like, of which the following is a specification, reference being had to the accompanying drawing, forming part thereof.

The figure is a perspective view of a corner piece for trunks, suitcases and the like, showing my new design.

I claim:

The ornamental design for a corner piece for trunks, suitcases, and the like, as shown.

NATHAN GOLDSMITH.
